(57) **CLAIM**

The ornamental design for an electrical connector as shown and described.

DESCRIPTION

FIG. 1 is a bottom, front, left perspective view of an electrical connector according to our design;

FIG. 2 is a top, right, front perspective view thereof;

FIG. 3 is a bottom, left, rear perspective view thereof;

FIG. 4 is a top, right, rear perspective view thereof;

FIG. 5 is a bottom, right, front perspective view thereof;

FIG. 6 is a front elevation view thereof;

FIG. 7 is a rear elevation view thereof;

FIG. 8 is a right side elevation view thereof;

FIG. 9 is a left side elevation view thereof;

FIG. 10 is a bottom plan view thereof; and,

FIG. 11 is a top plan view thereof.

The broken lines in the drawings illustrate portions of the article that form no part of the claimed design.
